UNITED STATES PATENT OFFICE

147,812

DESIGN FOR A FLUORESCENT LIGHTING FIXTURE

Earl N. Picker, Overland, Mo., assignor to Day-Brite Lighting, Inc., St. Louis, Mo., a corporation of Missouri

Application September 28, 1946, Serial No. 133,630

Term of patent 14 years

(Cl. D48—23)

To all whom it may concern:

Be it known that I, Earl N. Picker, a citizen of the United States and a resident of Overland, in the county of St. Louis and State of Missouri, have invented a new, original, and ornamental Design for Fluorescent Lighting Fixture, of which the following is a specification, reference being had to the accompanying drawing, forming part thereof.

Fig. 1 is a perspective view of a fluorescent lighting fixture, showing my new design.

Fig. 2 is a bottom plan view.

Fig. 3 is a side elevational view.

Fig. 4 is an end elevational view looking at the end opposite from that shown in Fig. 1; and

Fig. 5 is an enlarged cross-sectional view on the line 5—5 in Fig. 3.

The characteristic features of my design reside in the portions shown in full lines.

I claim:

The ornamental design for a fluorescent lighting fixture, substantially as shown and described.

EARL N. PICKER.
